UNITED STATES PATENT OFFICE.

JULES D. BISCAYART AND FERNAND CAILLETEAU, OF ATLANTA, GEORGIA.

ATTACHMENT FOR OPERATING SWITCH-BUTTONS.

1,264,760.

Specification of Letters Patent. Patented Apr. 30, 1918.

Application filed August 14, 1917. Serial No. 186,246.

To all whom it may concern:

Be it known that JULES D. BISCAYART and FERNAND CAILLETEAU, citizens of the United States, residing at Atlanta, in the county of Fulton and State of Georgia, have invented 5 certain new and useful Improvements in Attachments for Operating Switch-Buttons; and they do hereby declare the following to be a full, clear, and exact description of the 10 invention, such as will enable others skilled in the art to which it appertains to make and use the same, reference being had to the accompanying drawings, and to the letters and figures of reference marked thereon, which form a part of this specification.

This invention relates to new and useful improvements in electric light snap switches, the object in view being to produce a simple and efficient device of this nature which may be readily attached to an electric switch button and comprises a gravity actuated pawl carrying member adapted to cause a ratchet wheel fixed to the button clutch to make a partial rotary movement.

25 The present invention comprises various details of construction, combinations and arrangements of parts which will be hereinafter fully described, shown in the accompanying drawings and then specifically defined in the appended claims.

30 The invention is illustrated in the accompanying drawings which, with the letters of reference marked thereon, form a part of this specification and in which:

35 Figure 1 is an elevation showing the device applied to a switch button.

Fig. 2 is a detailed elevation of the inner face of the device, and

40 Fig. 3 is a central sectional view through the device.

Reference now being had to the details of the drawings by letter:

A designates a plate of any suitable material and provided with a circumferential flange B'. Said plate is provided with an 45 aperture C in which a pivotal pin D is mounted and upon which pin a ratchet wheel E is journaled. Said wheel is provided with slots F adapted to receive lugs H of the button clutch member K, said lugs being passed through the slots and suitably clenched. Said button clutch member is provided with laterally extending fingers, 50 designated respectively by letters I, K², L and M, the said fingers being bent parallel

to each other and spaced apart sufficiently to receive the button O. The finger K² is provided with a lug K' bent at right angles thereto and adapted to engage over the end of the button, and the finger L is provided with a similar lug L', designed to be bent at right angles over the opposite end of the button, thereby forming efficient means for securely holding the device upon the switch button. Struck up from the said plate are 60 lugs R and S which serve to retain the cylindrical outlined weighted member T in place between the flanges of the plate and which flanges partially cover and obscure the weight. Another lug, designated by letter 65 Q, is struck up from the flange of the plate, and I² designates a pawl which is provided with laterally extending pintles I² pivotally mounted in apertures in the lug Q and an aperture in the plate, said pawl being 70 adapted to engage the teeth of the ratchet wheel.

In order to limit the outer throw of the pawl a lug G is struck up from the plate and is inwardly bent and is in the path of 80 the pawl. A portion of the plate has a contracted extension A' which is laterally bent and apertured for the reception of the cord or chain J forming means whereby the plate may be tilted, it being noted that the point 85 of connection of the cord or chain is at the end of the plate opposite the one to which the weight is connected, the parts being so adjusted that when the cord is pulled upon for the purpose of rocking the plate, the latter will return, through the revolutions of the plate to its normal position, as the cord or chain is released.

90 In operation the button clutch is fitted over the button and the lug bent to hold the 95 same securely in place thereon. The normal position of the plate is shown in the drawings in which the weight will hold the plate in a vertical position. When it is desired to turn the switch, the operator, by 100 pulling down upon the cord, will cause the plate to tilt and with it the pawl engaging one of the teeth of the ratchet wheel will cause the latter to be given a partial rotary movement and as the clutch is fixed to the 105 ratchet wheel and the button fastened to the clutch, the button will be given a partial rotary movement sufficient to open or close the circuit of the lamp to which the switch is connected. When the cord or chain is re- 110

leased, the weight will return the plate to its normal position, the pawl turning idly over the ratchet teeth.

What we claim to be new is:

- 5 1. An attachment for buttons of snap switches, comprising an elongated plate with a laterally extending circumferential flange about the marginal edge thereof, a lug struck up from the flange at one end of the plate and other lugs from the body of the plate, a weighted member positioned intermediate the flanges and engaging the said lugs, a ratchet wheel journaled upon the plate, a button clutch member fastened to 10 the ratchet wheel and having laterally extending parallel fingers for engaging the button of a switch, a pawl pivotally mounted upon the plate and engaging the teeth of the ratchet wheel and a cord connected to 15 the plate and opposite the weighted member.
- 20 2. An attachment for buttons of snap switches, comprising an elongated plate with a laterally extending circumferential flange about the marginal edge thereof, a lug struck up from the flange at one end of the plate and other lugs from the body of the plate, a weighted member positioned intermediate the flanges and engaging the said lugs and having slots therein on either side of its frictional point, a button clutch member having laterally extending lugs bent at an angle and engaging said slots and provided with outwardly projecting fingers bent parallel to each other and provided with angled lugs for engagement with the edges of the switch button, a pawl pivotally mounted upon the plate and adapted to engage the teeth of the ratchet wheel, and a cord connected to a projecting portion of the plate, as set forth.
- 25 3. An attachment for buttons of snap switches, comprising an elongated plate with a laterally extending circumferential flange about the marginal edge thereof, a lug struck up from the flange at one end of the plate and other lugs from the body of the plate, a weighted member positioned intermediate the flanges and engaging the said lugs, a ratchet wheel journaled upon 30 the plate, a button clutch member fastened to the ratchet wheel and having laterally extending parallel fingers for engaging the button of a switch, a pawl pivotally

mounted upon the plate and engaging the teeth of the ratchet wheel, a portion of the plate being contracted and outwardly bent provided with an aperture therein, a cord fastened in said aperture, as set forth.

35 40 45 50 55 60

3. An attachment for buttons of snap switches, comprising an elongated plate with a laterally extending circumferential flange about the marginal edge thereof, a lug struck up from the flange at one end of the plate and other lugs from the body of the plate, a weighted member positioned intermediate the flanges and engaging the said lugs and having slots therein on either side of its frictional point, a button clutch member having laterally extending lugs bent at an angle and engaging said slots and provided with outwardly projecting fingers bent parallel to each other and provided with angled lugs for engagement with the edges of the switch button, a pawl pivotally mounted upon the plate and adapted to engage the teeth of the ratchet wheel, and a cord connected to a projecting portion of the plate, as set forth.

In testimony whereof we hereunto affix our signatures in presence of two witnesses.

JULES BISCAYART.
FERNAND CAILLETEAU.
